UNITED STATES PATENT OFFICE.

ALICE T. WONG, OF KAPAA, KAUAI, TERRITORY OF HAWAII.

SHAMPOO COMB.

Application filed December 2, 1921. Serial No. 519,550.

To all whom it may concern:

Be it known that ALICE T. WONG, a citizen of the United States of America, residing at Kapaa, in the Island of Kauai and 5 Territory of Hawaii, has invented new and useful Improvements in Shampoo Combs, of which the following is a specification.

The object of the invention is to provide a simple and efficient construction of comb 10 adapted for head massage and shampoo service and capable of use as an applicator for working a cleansing, remedial, or tonic preparation or medicament into the scalp and to the roots of the hair, particularly 15 when the latter is of more or less heavy growth tending to interfere with the efficiency of methods ordinarily employed in this connection and consisting largely in the use of the fingers of the masseur or of a 20 brush not particularly designed and adapted for the purpose; and with this object in view the invention consists in a construction and combination of parts of which a preferred embodiment is shown in the accom- 25 panying drawings; wherein:-

Figure 1 is a perspective view of a comb embodying the invention.

Figure 2 is a sectional view taken diametrically of the same and indicating the 30 optional location of a sponge or like remedy distributing agency in the holder.

The comb is of annular form having a preferably imperforate band or holder 10

preferably flared as indicated at 11 toward its upper edge and open at the upper side to 35 give access to the interior of the comb, and the annular series of teeth 12 depending from the band or holder and may be either integral with or fixed to the band and of a sufficient resilience to avoid scarifying or 40 scratching the scalp while being of a sufficient stiffness to provide for overcoming the resistance offered by the hair and bringing the terminals of the teeth into contact 45 with the scalp.

The flare at the upper edge of the band or holder not only provides a better grip in manipulating the device as a means of holding the sponge 13 or other absorbent distributing medium in position for pressure 50 by the hand grasping the band to control the application of the tonic, medicament or remedial or cleansing agent to the scalp as the comb is manipulated to rub the scalp.

Having described the invention, what is 55 claimed as new and useful is:-

A shampoo comb of annular form having an open band carrying a depending annular series of teeth, the band being flared toward its upper edge to form an exterior grip and 60 an interior seat for a moisture distributing medium.

In testimony whereof she affixes her signature.

ALICE T. WONG.
